UNITED STATES PATENT OFFICE.

THOMAS H. GRADY, OF BROOKLYN, NEW YORK.

ELECTRIC ALARM-CLOCK.

SPECIFICATION forming part of Letters Patent No. 403,100, dated May 14, 1889.

Application filed February 9, 1889. Serial No. 299,291. (No model.)

To all whom it may concern:

Be it known that I, THOMAS H. GRADY, a citizen of the United States, and a resident of Brooklyn, in the county of Kings and State 5 of New York, have invented certain new and useful Improvements in Electric Alarm-Clocks, of which the following is a specification.

The invention relates to improvements in 10 electric alarm-clocks; and it consists in a clock in which the electro-magnets are within the clock, and the armature thereof connected with or forming a part of the usual hammer for the gong, which remains in its customary 15 position.

In accordance with the invention the dial 20 of the clock is of non-conducting material and provided with a series of apertures at the outer edges of the line of numerals, in line with an aperture in the revoluble glass face, in order that a post connected with one 25 terminal of the circuit may be inserted through said aperture in the glass front into the proper aperture in the dial in position for 30 a hand traveling with the usual hour-hand of the clock to come into contact with it, and thus complete the electric circuit and cause the sounding of the alarm, the ringing continuing as long as said hand is in contact 35 with said post, which is only removable by the act of the person. The alarm will thus sound until the person arises and withdraws the plug from the face of the clock, this act breaking the circuit and stilling the alarm.

35 The invention will be more fully understood from the detailed description hereinafter presented, reference being had to the accompanying drawings, in which—

Figure 1 is a front view, partly in section, 40 of a clock constructed in accordance with the invention, the glass face of the clock being removed, and a portion of the dial being broken away for the purpose of disclosing the interior mechanism. Fig. 2 is a vertical section 45 of same on the dotted line XX of Fig. 1; and Fig. 3 is a detached view of the extra hand, which travels with the hour-hand of the clock and forms the circuit at the time it is desired that the alarm should sound.

50 In the drawings, A designates the casing of the clock; B C, the base or legs thereof; D, the usual bell; E, the dial, and F the glass face. The casing A is formed of sheet metal,

and is insulated from one leg, B, as shown in Fig. 1, the other leg, C, being in electric connection with the casing. The conductors G H from the battery (not shown) connect with the legs B C, as indicated in Fig. 1. The clock is provided with the customary works and hands, and in addition the supplemental 55 hand I, which has upon its inner portion the sleeve J, encircling the usual post, L, and said hand, when in use, will be directly below and travel with the hour-hand a of the clock. To the frame supporting the clock mechanism 60 are secured the electro-magnets N and post O, the latter being connected by wire P with the leg B of the clock, the said wire P being suitably provided with insulating material, in order that its contact with the frame M may 65 not disturb the electric current. On a bracket, Q, and insulated therefrom, is secured the spring R, (shown more clearly in Fig. 1,) and to this spring is attached the armature S, which forms a part of the support for the 70 hammer T.

The normal position of the spring R is 75 against the inner end of the adjustable screw V, which passes through the post O, above referred to, the armature S being thus held from 80 contact with the cores of the electro-magnets N by the tension of the said spring. The electro-magnets N are connected by a conducting-wire, W, with the spring R, and by 85 the conductor Y with the metallic plug or post Z, said conductor Y being suitably wrapped for the purpose of insulating it and enhancing its appearance, and the plug Z having an appropriate handle, b.

The dial E is made of non-conducting material—such as hard rubber or celluloid—and upon its face is applied a paper disk, c, upon which the customary numerals are printed. The dial E contains a line of apertures, d, encircling the series of numerals and in position 95 to be traversed by the supplemental hand I, as indicated in Fig. 1. The glass face F is held in the recesses e at the outer edges of the clock-casing, and said face is revoluble at will. In the face F is provided an aperture, f, which is in a position to be moved over any one of the apertures d in the dial E.

In the use of the invention the person setting the alarm will insert the end of the plug Z in the aperture f and revolve the face F to 100 such position as will enable him to move the

plug Z into the aperture *d* adjacent to the hour at which he desires the alarm to sound—as, for instance, "VI" o'clock, which is the position of the plug Z illustrated in Fig. 1.

5 The plug being in use, the supplemental hand I will at the hour come into contact with the same and complete the electric circuit, the current from the wire H passing through the leg C, casing A, clock mechanism, hand I, 10 plug Z, and conductor Y to the magnets N, and from the magnets through the conductor W to the spring R, which is in electric connection through the post O, wire P, and leg B with the other wire, G, from the battery.

15 Upon the hand I coming into contact with the plug Z the current entering the electro-magnets N will cause the cores thereof to attract the armature S toward them, causing the hammer T to strike the bell D and breaking 20 the contact of the spring R with the screw V, this latter action breaking the circuit at the point of the screw V, which has the effect of causing the cores of the electro-magnets to instantly release the armature S and permit 25 the hammer T to recede from the bell D, and the spring R to regain its contact with the screw V, thereby again completing the circuit, whereupon the armature S will be again attracted by the electro-magnets and the bell 30 again struck by the hammer T. The armature is thus caused to rapidly vibrate between the screw V and the electro-magnets N until the plug Z shall have been withdrawn from the apertures *f d*, the hammer T striking the bell 35 D with each vibration of the armature. It is obvious that the ringing of the bell will continue until the person arises and withdraws the plug Z from the clock-face, at which time the alarm will cease.

40 The purpose of the hand I is simply to have a conductor between the post L and the plug Z, and it is obvious that if the hour-hand *a* were sufficiently long the hand I might be omitted. When, however, the hand I is made 45 use of, the usual clock-hands may be employed without altering their form or length, and hence, for the sake of convenience, I employ the supplemental hand I.

45 The setting of the alarm consists in simply inserting the plug Z through the aperture *f* and into the aperture *d* at the hour at which it is desired the alarm shall sound, and the convenience of this portion of the invention is apparent.

50 The form of the clock constructed with my invention remains unchanged, and an ordinary bell in its customary position is made use of without alteration. The electro-magnets, being within the clock-casing, are concealed from view, and are unobjectionable.

55 The conductor Y being flexible, the plug Z may be dropped beneath or behind the clock-casing, thus forming no obstruction or disfigurement.

60 By making the glass face F revolute but one aperture *f* is necessary therein; but should it be desired to have a stationary glass face

on the clock, a row of apertures therein corresponding with the series of apertures *d* would be required in order that the plug Z 70 might be inserted at the various positions desired.

What I claim as my invention, and desire to secure by Letters Patent, is—

1. In an electric alarm-clock, the dial of 75 non-conducting material provided with the line of apertures, and the revoluble transparent face provided with an aperture in position to be brought over any one of the apertures in the dial, combined with the movable plug connected with a conductor from the electro-magnets and adapted to be inserted through said apertures, the vibrating armature connected with the bell-hammer and arranged between the electro-magnets 80 and the back contact, the latter being in connection with one wire of the battery, and a hand upon the clock forming a conductor through the clock mechanism to the other wire of the battery and adapted during its 85 travel to come into contact with the plug in said apertures, substantially as set forth.

2. In an electric alarm-clock, the dial of 90 non-conducting material provided with the line of apertures, and the transparent revoluble face provided with an aperture in position to be brought over any one of the apertures in the dial, combined with a movable plug adapted to be inserted through said apertures in the desired position, and a hand 95 traversing the dial and of a length to be arrested by contact with said plug, the hand and plug forming the terminals of the electric circuit in which the alarm-hammer is connected with the vibrating armature, substantially 100 as set forth.

3. In an electric alarm-clock, the hammer and bell, the dial having the series of apertures, and the transparent face having an aperture in line with the apertures in the 105 dial, combined with the movable plug adapted for insertion into said apertures, the hand traversing said dial and of a length to be arrested by said plug, and an electric circuit of 110 which said hand and plug are the terminals, 115 and in which the armature is connected with the said hammer, substantially as set forth.

4. An alarm-clock having its bell-hammer connected with the armature in an electric circuit, and a dial having a series of apertures, combined with a hand traversing the 120 dial and extending to said apertures, and a removable plug adapted to be inserted into 125 said apertures and to arrest said hand, the hand and plug forming the terminals of the circuit, substantially as set forth.

Signed at New York, in the county of New York and State of New York, this 7th day of February, A. D. 1889.

THOMAS H. GRADY.
